UNITED STATES PATENT OFFICE.

SIDNEY E. HUMPHRYS, OF TOLBERT, TEXAS.

RAILROAD-SIGNAL.

1,331,434.

Specification of Letters Patent. Patented Feb. 17, 1920.

Application filed March 17, 1916. Serial No. 84,884.

To all whom it may concern:

Be it known that I, SIDNEY E. HUMPHRYS, a citizen of the United States, residing at Tolbert, in the county of Wilbarger 5 and State of Texas, have invented new and useful Improvements in Railroad-Signals, of which the following is a specification.

This invention relates to automatic train stopping systems and more particularly to a 10 system by means of which trains will be prevented from colliding at railway crossings.

The primary object of the invention is to provide a system of simple construction in 15 which the parts are so correlated as to necessitate only a single source of current thus obviating the disadvantages of the use of a number of sources of current.

An object of the invention is the equipment 20 of the approaches of a single track crossing with novel circuit closing means controlled by a device carried by a train.

A further object is the provision of novel 25 electro-mechanical means for controlling the operation of semaphores for notifying the engineer of an approaching train and indicating whether the track is clear.

A still further object is to provide in conjunction with the semaphore positive means 30 for stopping the train should the signal be ignored, said means being electro-mechanically operated in conjunction with the semaphores.

With this and other objects in view the 35 invention consists in the construction, combination and arrangement of parts as will be hereinafter more fully described and illustrated in the accompanying drawings and pointed out in the claims hereunto appended.

40 Referring to the drawings:

Figure 1 is a diagrammatic view of the circuits and devices for operating the apparatus adjacent to one track, and showing the track switches of the intersecting track 45 (the relative position of all apparatus with reference to the crossing being shown diagrammatically in Fig. 11).

Fig. 2 is an enlarged diagrammatic view 50 showing the switch at the extreme right closed (by the operation of the contact rail of Figs. 4 and 5), the switch arms in the base of the semaphore being in normal position.

Fig. 3 is a similar view, the switch arms 55 being in a different position, after operation.

Fig. 4 shows the train carried apparatus and its relation to the contact rail.

Fig. 5 shows the contact rail and associated elements.

Fig. 6 is a top plan view showing the position of the track elements; also showing a portion of the train carried device. 60

Fig. 7 is a vertical section through the semaphore base, the apparatus therein being in elevation. 65

Fig. 8 is a section on line 8—8 of Fig. 7.

Fig. 9 is a section on line 9—9 of Fig. 7.

Fig. 10 is a similar section, through the switch arms only showing the release catch engaged by a stationary element referred to 70 below.

Fig. 11 is a diagrammatic view showing the relative position of the pieces of apparatus at the point where two tracks intersect. 75

The numeral 1 designates a casing forming a base of a semaphore, the arm of which is actuated by a cable 3 connected with a drum referred to below. Slidably mounted in a portion of each casing 1 is the rod 4 80 moving in a direction toward the center of the trackway. At an intermediate point the rod 4 is provided with a pin 5 engaging a bifurcated end of a bell-crank lever 6 that has its remaining end pivotally connected to one end of a link 7; the other end of the latter being connected by other links to one end of a switch arm 8.

The switch arm 8 is pivotally connected to the casing as indicated at 9; and the upper 90 end thereof, as illustrated in the drawings is provided with a contact plate 10 co-operating with the contact finger 11 upon a second switch arm 12 also mounted upon the pivot 9. 95

The second switch arm 12 also carries a second contact finger 13 engaging contact rod 49 for a purpose hereinafter described. These switch arms 8 and 12 are held associated with each other in their downward 100 arcuate movement until they have assumed substantially a horizontal position when they are separated from each other in a manner now to be described. The arm 12 has formed therein a recess 14 in which is arranged a 105 trigger 15 forced in a direction to engage the under surface of the arm 8 by means of a coiled spring 16. The arm 12 is provided with a plate 17, one purpose of which is to co-operate with trigger 15 for preventing 110 independent movement of the arms; other purposes will be described below. For separating the arms when they reach a horizontal position I mount upon the bottom of

Fig. 4 shows the train carried apparatus and its relation to the contact rail.

the casing 1, a rod 18 so arranged as to engage the inclined surface 19 of the trigger and force the latter in a direction to disengage the under surface of the switch arm 8 and thus allow the switch arm 12 to ascend for accomplishing the results which will be described later. The semaphore and the switch arms are simultaneously moved by the following apparatus.

10 A motor 20 has mounted upon its shaft a drum 21 receiving a cable 22 attached to the switch arm 8 and the drum 23 receiving the cable 3. The drums are held against retrograde movement through the action of a ratchet 24 upon the motor shaft co-operating with a link 25 the latter being connected to latch 26' and actuated in any suitable manner such as by movement of the armature 26 by the influence of the magnet 27. The 15 curved end of arm 8 permits it to pass the hook portion of the latch and then engage the latter.

15 For preventing the switch arm 12 from returning completely to its normal position for a purpose hereinafter described I provide a magnet 28 the armature 29 being connected to arm 29', one extremity of which being connected to a pivot lever 30 arranged to assume a position in the path of movement of the switch arm 12. This construction is shown in Figs. 8 and 10. See, also 20 Figs. 2 and 9. The numeral 31 indicates a spring so arranged as to act upon the armature 29 and hold the lever 30 out of the path of movement of the switch arm 12. The lever 30 is of insulating material and carries a contact plate 30' for the purpose described below.

It is to be understood that there are four 25 pieces of apparatus of the type shown in Fig. 7, and in the diagrammatic views they are designated A and B and A' and B'. A and B are located along the track 2, and A' and B' are located along the track 2', as 30 shown in Fig. 11.

The mechanism for actuating the switch arm 35 is better illustrated in Figs. 4 to 6 inclusive of the drawings wherein is shown a contact rail 51 supported by plungers 52 working in cylinders 53 against the action of coil springs 54. At an intermediate point the rail 51 is provided with a depending rod 55 working in a tubular extension 56 formed on a casing 57 that houses the switch arm 35 and its associate parts. There are four switch arms 35 with their associated parts, the same being located along tracks 2 and 2' as shown in Fig. 11, at the points a, b and a' and b'. For depressing the contact rails 51 in order to close a circuit I mount upon the cow-catcher 58 of the locomotive a frame 59 supporting wheels 60 arranged to ride upon the upper surface of the rail. In addition I provide the stem 62 of the valve 63 of the air brake system with an extension 64 so

arranged as to engage the rod 4 when the latter is thrown into a danger position.

The first position of arms 8 and 12 is shown in Fig. 2, a train having approached from the right and depressed lever 35 of b, 70 closing the circuit of A' (Figs. 1 and 11) as follows:

From battery 32 through wires 33', 33, contact 34, switch arm 35 of b, wire 37', wire 37 of A', pivot 9, wire 38, plate 17, contact 11, plate 10, wire 39, to motor 20, wire 40, wire 32^a, to battery 32. (The circuit including magnet 27 may at this time be energized, but the magnet has no function in this operation.) The magnet 28 is also energized, but element 30 is held against movement by arm 8. The circuits for the mechanism at B' may be traced in a similar manner.

When the motors of A' and B' start, they 85 wind the cables 3, raising the semaphores, and also the cables 22, lowering switch arms 8 and 12, the arms 8 throwing rods 4 for engaging valve operating device 64, of Fig. 4, described elsewhere. (The circuits for 90 magnets 27 are now broken.)

When switch arms 8 and 12 of B' reach their lower position, arm 8 is locked by latch 26', the arm 12 is released by rod 18 engaging pivoted device 15, and the circuit for the 95 motor is broken. Arm 12 is raised by spring 42, this arm in apparatus A' striking the contact 43, forcing it against plate 30' of lever 30, while the plate 17 on switch arm 12 of B' makes contact with plate 30' of lever 30, this lever stopping arm 12, magnet 28 being still energized. This magnet is included in the circuit from battery 32, through wires 33', 33, contact 34, switch arm 35 of b, wire 37', wires 37, 40^a, magnet 28, 105 wires 40', 40, wire 32^a, to battery 32. This position of the arms is shown in Fig. 3.

When arms 8 and 12 are in this position, current also passes from wire 37 of B' to pivot 9, wire 38 to plate 17, plate 30' on lever 110 30, wire 44, to plate 30' on lever 30 of A', contact 43, wires 46, 47, magnets 48, wire 32', wire 32^a, to battery 32. This energizes magnet 48 of b releasing arm 35 and breaking the circuit, and also breaking the circuit of magnets 28 of A' and B', the springs on arms 29' drawing levers 30 out of the way of switch arms 12, and the latter striking stops 12' as they resume their normal position. The elements are now in the position shown in Fig. 1.

The semaphores of A' and B' now remain in their elevated position, the ratchet members locking the drums, and the switch arms 8 being locked in their lower position, 125 keep the rods 4 projected.

A train is now passing over the crossing from the right in Fig. 11.

The semaphores and rods 4 of A' and B' on track 2' have been set so that the engi- 130

neer on a train approaching in either direction on track 2' will be notified, and should the semaphore be ignored the train will be stopped when rod 4 engages valve operating device 64 shown in Fig. 4. The elements remain in this position until the train passes the crossing, when lever 35 of A is depressed for closing the circuits described below:

Contact 13 on plate 17 of arm 12 rests against rod 49 of A', and current passes from battery 32 through wires 33', 33, contact 34, lever 35 of A, wires 37', wire 37, pivots 9, wires 38, plates 17, contacts 13, contact rods 49, wires 50, magnets 27, wires 40, 32^a to battery 32. The circuit through B' is similar. Shunt circuits are completed as follows: The current passing over wire 40^a and wire 40' energizes magnets 28, causing them to project levers 30. Magnets 27 are thus energized, through wires 50, opening latches 26' and releasing arms 8, and ratchet devices 25. Arms 8 and cables 22 operate drums 21 and 23 for lowering the semaphores.

The switch arms 8, through the action of springs 66 move upwardly until they strike levers 30. Current now passes from wire 33 to wire 45, contact plate 45', on switch arm 8, to plate 30' on lever 30 of B', to wire 44, to plate 30' and contact 43 of A' which has been pressed against plate 30' by arm 8, the current passing thence through wires 46, 47, magnet 48 of a, wires 32', 32^a, to battery 32.

The magnet 48 of a when energized releases lever 35, breaking all of the circuits, including magnets 28, allowing the switch arms to resume their normal position.

The train having passed the crossing, all of the elements return to their normal position, and are again ready to be acted upon.

The operation of a' and b' and A and B is similar involving similar circuits. Wires 70, 71, 72 lead to apparatus A and B of Fig. 11.

It is to be understood that while all of the several features of my improved system have special coöperation with one another and together constitute a particularly effective system for the purpose in view certain of these features may be applied in other relations and I therefore desire to cover the combinations present in the several parts of my improved system whether employed in a general organization shown or elsewhere.

What I claim is:—

1. In an automatic train stop system a track apparatus comprising a rod mounted

for reciprocatory movement, an electro-motor, electro-mechanical means for energizing said motor, a switch arm and rod-projecting means connected therewith establishing a connection between said motor and said rod and means associated with said switch arm for energizing said motor and said electro-mechanical means, the aforesaid electro-mechanical means for energizing the motor including a train-operated switch.

2. In an automatic train stop system a track apparatus comprising a rod mounted for reciprocatory movement, an electro-motor, electro-mechanical means for energizing said motor, a switch arm and rod-projecting means connected therewith establishing a connection between said motor and rod and means associated with said switch arm for energizing said motor in one position of the switch arm, energizing said electro-mechanical means in another position of the switch arm and breaking the motor circuit in a third position of the switch arm, the aforesaid electro-mechanical means for energizing the motor including a train-operated switch.

3. In an automatic train stop system a track apparatus comprising a rod mounted for reciprocatory movement, an electro-motor, a circuit including a train-operated switch, a pair of switch arms and rod-projecting means connected therewith establishing a connection between the motor and said rod and coöperating to close the motor circuit and means for separating the said arms for breaking the motor circuit.

4. In an automatic train stop system a track apparatus comprising a rod mounted for reciprocatory movement, an electro-motor, a pair of switch arms and rod-projecting means connected therewith establishing a connection between the motor and said rod and coöperating to close the motor circuit and means for separating the said arms for breaking the motor circuit, electro-mechanical means for energizing the motor and means associated with one of said switch arms when the latter is in one position for rendering said electro-mechanical means active, the aforesaid electro-mechanical means for energizing the motor including a train-operated switch.

In testimony whereof I affix my signature in presence of two witnesses.

SIDNEY E. HUMPHRYS.
